UNITED STATES PATENT OFFICE.

EPPA H. RYON, OF WALTHAM, MASSACHUSETTS, ASSIGNOR TO CROMPTON & KNOWLES LOOM WORKS, OF WORCESTER, MASSACHUSETTS, A CORPORATION OF MASSACHUSETTS.

SHUTTLE-CHANGING LOOM.

Application filed April 2, 1923. Serial No. 629,243.

To all whom it may concern:

Be it known that I, EPPA H. RYON, a citizen of the United States, residing at Waltham, in the county of Middlesex and State of Massachusetts, have invented a new and useful Shuttle-Changing Loom, of which the following is a specification.

This invention relates to a shuttle changing loom of the general type disclosed in my prior application, Serial No. 414,046 filed October 1, 1920.

It is the object of my present invention to improve the mechanism therein shown and described, to the end that the construction may be simplified, that the operation of the loom may be made more certain, and that damage and breakage of the parts may be reduced or avoided. Different features of my invention relate to arrangements and combinations of parts which will be hereinafter described and more particularly pointed out in the appended claims.

A preferred form of my invention is shown in the drawings, in which—

Fig. 1 is a side elevation of a loom embodying my improvements;

Fig. 2 is a front elevation of the shuttle-changing end of the lay;

Fig. 3 is a plan view of the parts shown in Fig. 2;

Fig. 4 is an end elevation of the shuttle transfer receptacle;

Fig. 5 is a partial plan view thereof, broken away to show certain mechanism;

Fig. 6 is a plan view of the transfer receptacle and the shuttle storage compartment;

Figs. 7, 8 and 9 are diagrammatic sectional elevations illustrating the discharge and replacement of an exhausted shuttle;

Fig. 10 is a detail plan view of the shuttle holder;

Fig. 11 is a front elevation of the actuating mechanism for the shuttle changer, taken substantially along the line 11—11 in Fig. 1;

Figs. 12 and 13 are detail sectional views taken along the line 12—12 in Fig. 1 and showing the parts in different operating positions; and

Fig. 14 is a detail side elevation of a part to be described.

Referring to the drawings, I have shown a loom which is similar in a general way to

the loom shown in my prior application. 55 The loom comprises an end frame or loom side 20 on which is mounted a shuttle magazine 21 from which the shuttles S are successively delivered to a shuttle holder 22. The holder 22 is normally maintained in 60 the rearward or operative position shown in Fig. 1, and upon indication of weft exhaustion the lifter rod 23 is actuated to raise the shuttle S as indicated in Figs. 7 and 8 and to simultaneously eject the exhausted 65 shuttle S' as indicated in Figs. 8 and 9.

A shuttle binder 24 (Fig. 2) is pivoted at 25 to a bracket 26 fixed in vertical position on the lay end 27. A spring 28 forces the binder inward against the shuttle and 70 a stop 29 limits outward movement thereof. The binder 24 is provided with an upward extension 30 which remains in contact with the exhausted shuttle S' as the shuttle is raised to the ejecting position shown in 75 Fig. 8. When the fresh shuttle S is picked from the shuttle box, the binder is moved rearward by the spring 28 and the upward projection 30 of the binder assists in ejecting the shuttle S' as indicated in Fig. 9. 80 The binder 24 is also provided with a downwardly extending lug or projection 31 which is curved forwardly to provide a guide for the shuttle S as it is raised to operative position.

The construction of the shuttle holder 22 has been improved in important details best shown in Fig. 10. The holder 22 now comprises a substantially rectangular box-like framework 32 mounted to slide in fixed 90 guide-ways supported in the frame 20. The shuttle is supported upon a pair of lugs or projections 33 extending rearward from the framework 32 and rigidly secured thereto, as by rivets 34. The shuttle is positioned 95 longitudinally on the supports 33 by a single continuous band 35 of spring steel fixed to the rear face of the framework 32. The holder thus constructed is more substantial than that shown in my prior application 100 and is less liable to injury or distortion when in use.

The shuttle S', when ejected from the raised shuttle box, is received in a transfer receptacle 37 pivoted at 38 to the ends of 105 an arm or lever 39 by which the receptacle may be raised to deliver the shuttle to the storage compartment 40. A stud 41 in the

end of the transfer receptacle 37 is guided in a cam slot 42 on a bracket 43 as the receptacle is raised, thus tilting the receptacle as indicated in Fig. 1.

5 The receptacle 37 as thus far described is substantially the same as in my prior application but I have improved the construction of this earlier receptacle by providing a hinged rear wall 45 which is pivotally mounted upon a cross rod 46 supported beneath the receptacle and is yieldingly held in closed position by a coiled spring 47 on the rod. The yielding rear wall of the receptacle is of great advantage when a shuttle is discharged in improper position, as occasionally happens. Under these conditions the rear wall will yield to permit the end of a misplaced shuttle to be thrust backward, thus avoiding the breakage which has 20 heretofore occurred.

For the same purpose I have also provided a yieldingly mounted guide or supporting plate 50 over which the ejected shuttle passes to the receptacle 37. This plate 50 is secured to the lower end of arms 51 mounted on fixed pivots 52 and yieldingly drawn forward by a spring 53 against a stop pin 54. Under normal conditions the plate 50 remains substantially in the position indicated 30 in Fig. 1 but it may readily yield and be swung backward if engaged by a misplaced shuttle.

Applications have been heretofore filed for certain improvements on the driving mechanism disclosed in my prior application, said application being filed in the names of A. J. Chevrette and R. G. Turner, Serial Nos. 598,123, and 598,110, both filed August 31, 1922.

40 It is a further object of my present invention to improve the mechanism shown in said later applications, by providing a spring so connected to the clutch lever that it will hold the driving pinion yieldingly in either 45 operative or inoperative position. This construction is shown in Figs. 11, 12 and 13, of the drawings and comprises a tension spring 60 secured at one end to a fixed lug or bracket 61 and at the opposite end to a projection 50 62 on an upwardly extending arm 63 of the belt crank 64 by which the clutch pinion 65 is shifted on the continuously driven cam shaft 66. The arm 63 is forked at its upper end to receive studs 67 on a yoke collar by which the pinion is engaged. The lugs or 55 projections 61 and 62 are so positioned that the spring 60 will be disposed at opposite sides of the axis of the bell crank 64 in the two positions shown in Figs. 12 and 13, thus having a toggle action to yieldingly prevent displacement of the parts.

60 In Fig. 14 I have shown an adjustable yielding connection which permits a delay in the shifting of the clutch pinion 65 until the parts of the clutch are properly aligned.

For this purpose, I provide a link comprising a rod 70 extending freely through an opening in the end of a rod head 71 and having a spring 72 mounted thereon. Lock nuts 73 threaded on the rod 70 retain the spring 70 in position and also permit the same to be adjusted. The spring 72 normally holds a collar 74 on the rod 70 in contact with the end of the head 71, but if the link is pulled downward when the recesses in the clutch 75 collar are out of alignment with the clutch pins the spring 72 will be compressed and the head 71 may be moved downward without corresponding movement of the rod 70.

The general construction and operation of 80 my improved loom is fully disclosed and described in my prior application above noted and reference is made thereto for a complete description thereof.

Having thus described my invention, I do 85 not wish to be limited to the details herein disclosed otherwise than as set forth in the claims but what I claim is:—

1. In a shuttle changing loom, a shuttle transfer receptacle and elevating mechanism 90 therefor, said receptacle having its back wall mounted for rearward yielding movement to prevent damage from a misplaced shuttle.

2. In a shuttle changing loom, a shuttle transfer receptacle, a shaft mounted thereon, 95 said receptacle having its back wall pivoted on said shaft, and a spring to move said wall yieldingly to closed position.

3. In a shuttle changing loom, a lay, shifting shuttle boxes thereon, a spent shuttle 100 storage, a movable shuttle transfer receptacle effective to transfer spent shuttles to said storage, and means to guide a shuttle from said lay to said transfer receptacle, said means including a guide plate interposed between said lay and said transfer receptacle at the rear of said lay, and means to hold said plate yieldingly in position.

4. In a shuttle changing loom, a lay, shifting shuttle boxes thereon, a spent shuttle 110 storage, a movable shuttle transfer receptacle effective to transfer spent shuttles to said storage, and means to guide a shuttle from said lay to said transfer receptacle, said means including a movably mounted 115 guide plate positioned at the rear of the lay, and a spring to hold said plate yieldingly in normal forward position.

5. In a shuttle changing loom, a slidably mounted shuttle holder comprising a rectangular rigid frame, shuttle supporting lugs fixed thereto, and a single strip of resilient metal secured to the rear face of said holder and bent to enclose both ends of a shuttle supported on said holder.

6. In a shuttle changing loom, in combination, a lay, a shuttle box mounted for vertical movement thereon and having running and discharge positions, and a binder mounted at a fixed elevation on said lay to 130

engage a shuttle in said box when the latter is in running position, said binder having an upwardly extending portion also effective to engage and assist in ejecting an exhausted shuttle when the box is in discharge position.

7. In a shuttle changing loom, in combination, a lay, shifting shuttle boxes movably mounted thereon, means to shift said boxes to raise an exhausted shuttle to discharge position and a fresh shuttle to running posi-

tion, and a single binder mounted on the lay independent of the movable boxes, said binder engaging the running shuttle and having projecting portions engaging the entering fresh shuttle and also the outgoing exhausted shuttle, until the discharge of the latter. 15

In testimony whereof I have hereunto affixed my signature.

EPPA H. RYON.
